UNITED STATES PATENT OFFICE

JAMES E. BUSHNELL, OF NORTH PLAINFIELD, NEW JERSEY, ASSIGNOR TO RANSOME CONCRETE MACHINERY COMPANY, OF PLAINFIELD, NEW JERSEY, A CORPORATION OF NEW JERSEY

CONCRETE ELEVATING AND DISTRIBUTING APPARATUS

Application filed January 4, 1928. Serial No. 244,394.

This invention relates to concrete distributing apparatus and more particularly to the buckets or loaders for the batch, their arrangement and the hoisting thereof to the desired level for gravity distribution of the batch, and means for dumping their contents.

Apparatus of this character usually comprises an upright tower member or mast, a bucket to receive and elevate the batch, a hoisting mechanism or elevator therefor, an elevated receiving hopper and conducting chutes with suitable means for their support to deliver the material received from the bucket to various points over a given area. It is the practice to mount these buckets for vertical movement either inside the mast or tower, or outside same at one side thereof. Such plants have been built in sizes up to 20 and including what is known in the trade as the $\frac{3}{4}$ -yard size. The bucket, of course, having $\frac{3}{4}$ of a cubic yard capacity. The loads, which the mast must withstand during the hoisting and dumping operation of the bucket, are such that they produce an eccentric or twisting force on the mast, regardless of how carefully it may be guyed. In addition to this torque set up in the mast, the hoisting operation, the shock to the mast 30 as the bucket is tripped and the momentum of the load as the batch leaves the bucket sets up a severe vibration in the mast. The present improvements are directed to the elimination or the reduction to a minimum 35 of the undesirable forces and vibration aforementioned.

The primary object, among others, is to provide such an arrangement and proportion of parts that it is possible to use hoisting equipment having a greater capacity without placing any materially greater load on the mast or tower, in any manner, than has been placed in the past by plants having smaller capacity. This result is accomplished by the use of twin hoist buckets symmetrically arranged with respect to the mast 40 so that the forces which the mast must withstand when the buckets are hoisted and dumped are so applied in relation to the mast that they produce little torque or vi-

bration. The arrangement is such that the weight and shock of the loaded buckets and the concrete leaving each of them is evenly distributed, so that there is an equalization of the forces about the mast. During the 55 dumping operation, the concrete leaving each of the twin buckets may be but a fraction of that leaving the single bucket and because of the smaller size bucket, the total distance of fall and therefore the impact and 60 vibration are materially reduced.

The improvements fill a great need in the art, and accomplish all that the usual tower type, having a hoist bucket operating on the inside of the tower, can accomplish and may 65 be built of parts of a size and weight to be more economically transported, erected and operated.

Other advantages of the improvements will be apparent to those skilled in the art. 70

Referring to the drawings,

Fig. 1 is a view in side elevation of the improved bucket and hoist arrangement in connection with the familiar tower or mast;

Fig. 2 is a view similar to Fig. 1, looking 75 in the direction of the arrow;

Fig. 3 is a plan view of the structure;

Fig. 4 is a side elevation of a modified form;

Fig. 5 is a view similar to Fig. 4, looking 80 in the direction of the arrow;

Fig. 6 is a plan view of the modification.

Referring to the embodiment in Figs. 1-3, the usual mast or tower may be composed of a plurality of posts or uprights, preferably four indicated at 11, 11, 12, 13 all suitably braced to form the tower 10. Guy ropes or cables 14 attached to suitable cross beams 15 are employed for steadyng the mast and maintaining same erect. A hopper or bin 16, for receiving material from buckets, is suitably hung on a frame 17 mounted on the tower or mast and vertically adjustable therewith by means of cable 18 leading to a power means (not shown). The 90 hopper 16 is provided at its bottom with the usual discharge spout 19 for depositing the charge in distributing chutes, one only being shown at 20. As clearly seen in Figs. 2 and 3, the hopper extends a considerable 95

distance laterally of the mast and is provided, at its top on each side of the mast, with two inlets or receiving spouts 21, 22 for initially receiving the charges of the buckets. 5 Each inlet portion or spout carries a bucket switch or trip 23, which are rigidly mounted on that side of the mouth of each spout which is adjacent the mast, see Fig. 2. Said spouts are pivotally mounted on the hopper at 24, so that they may be swung outwardly 10 carrying trips 23, as indicated in dotted lines in Fig. 1, to clear the mast when the sliding frame 17 is shifted. Any convenient means may be provided for securing the frame 17 and spouts 21, 22 in operative 15 position.

On the side of the mast opposite hopper 16, is mounted a vertically movable carriage 25, having rollers 26 bearing on the flanges of the channeled rails 12 and 13. A suitable hoist cable 27 for said carriage has one end fixed at the top of the mast as at 28, and runs down through sheave 29, on carriage 25, up to the top of the mast through sheave 30 and thence to a suitable power actuated winding drum (not shown). It is apparent from this arrangement that the mechanical advantage secured enables the same amount of power applied in a single bucket plant, 20 to elevate the two bucket carriage. Inspection of the drawings will disclose four pairs of rollers, 26, the rollers of each pair being positioned 90° apart for bearing on two sides of rails 12 and 13. This construction 25 affords a sturdy truck and a reliable means for maintaining the carriage 25 in proper alignment with the mast at all times.

The carriage 25 comprises a bail 31 on which are mounted suitable cross beams 32 connected by uprights 33 defining an offset bucket carrying frame. As seen in Fig. 2, said frame defines three panels, one in the center substantially the width of the mast and one on either side thereof, projecting 30 laterally beyond the limits of the mast. In each of these outer panels is pivotally mounted a bucket 34 for hoisting the concrete. The buckets are of that common type which is normally counterbalanced on the side of their axes opposite rollers 35 so that the buckets themselves, as well as the loaded buckets, are normally stable on the carriage 25, being aided in this by chains 37, (see full line showing of bucket in Fig. 1). These 35 two buckets are of equal capacity and are normally maintained in upright position. Rollers 35, are provided on the nose of each bucket adjacent the mast, and are adapted 40 to ride in the trips 23 as hereinafter explained.

In operation, the hopper 16, spouts 21, 22 and trips 23 are adjusted at the desired elevation, as seen in full lines in Fig. 1. The buckets 34 are filled at the bottom of the 45 mast, preferably with an equal amount of

concrete. The power driven cable 27 hoists the carriage and buckets, the rollers 26 bearing on rails 12 and 13 to guide same and prevent lateral movement of the carriage and buckets with respect to the mast. As 70 the buckets approach spouts 21, 22, the rollers 35 thereon are caught in switches or trips 23 in which they ride. Upon further vertical movement of the carriage and buckets, the curved ends of switches 23, by 75 means of rollers 35, pull buckets 34 from their panels, further ascent of the carriage 25 raising the pivots of the buckets above the now downwardly directed discharge portions thereof. The buckets, at this point, 80 are in discharging position, as seen in dotted lines in Fig. 1, being held by the chains or cables 37 secured to the beams 32 and the buckets. As clearly apparent, the switches 23 are disposed in the path of the ascending 85 rollers 35, while buckets 34 when dumped are directly over the inlets or spouts 21, 22 of hopper 16.

The foregoing detailed description discloses the equalization of the load about the 90 mast, particular attention being called to the fact that the momentum of the mass, as it leaves the buckets and strikes the spouts, is experienced alike on directly opposite sides of the mast and in the axial plane thereof. 95 This centralization of the forces which the mast must withstand, eliminates or reduces to a minimum the severe vibration and torque set up therein.

It is apparent that upon lowering the carriage 25, the bucket pivots are lowered, 100 drawing the buckets out of switches 23, back into the panels to erect position in the carriage for receiving another charge.

The modified embodiment in Figs. 4-6 105 differs from the preferred form in that the buckets discharge away from the mast. In this form the hopper or bin 16 also has two inlets or spouts 40, 41, embracing the mast 10, but extending outwardly therefrom at an 110 angle, their ends, however, being parallel to the mast. As seen in Fig. 5, these spouts carry switches 43 positioned in alignment with rollers 44 of the buckets, and are pivotally mounted for swinging out of the path 115 of the bucket as in the preferred form. The hopper 16 is vertically adjustable on the mast as previously described. A carriage 45, having a suitable hoisting cable 46 is also provided, rollers 47 as aforementioned 120 bearing on rails 12 and 13 of the mast. An offset frame 48 mounted on the carriage supports the two pivotally mounted buckets 49, of the counterbalanced type described in the preferred form, said buckets, however, 125 dumping away from each other, instead of in parallel planes as in the preferred form. The operation and advantages of this form will be apparent from reference to the embodiment formerly described.

I claim:

1. The combination in apparatus of the character described of a rigid upright mast, a hopper for receiving material for distribution, pivotally mounted means for elevating material arranged to be elevated and lowered on said mast, and mechanism for elevating and lowering said means, said hopper having portions on two sides of said mast for receiving material from said means.

2. In apparatus of the character described, in combination, a rigid upright mast, a hopper having portions on two sides of the mast for receiving material for distribution, means comprising a plurality of buckets for elevating material arranged to be elevated and lowered on said mast and mechanism for elevating and lowering said means, said means positioned for concurrently discharging the contents of said buckets into said portions.

3. In apparatus of the character described, in combination, a rigid upright mast, a hopper for receiving material for distribution, a vertically movable carriage, a plurality of buckets pivotally secured thereto for elevating material arranged to be elevated and lowered on said mast, mechanism for elevating and lowering said carriage and buckets, said hopper having a receiving portion for each bucket, the discharge portion of each bucket and its hopper receiving portion being positioned inwardly with respect to front and rear faces of the mast.

4. The combination in apparatus of the character described of a rigid upright mast, a vertically adjustable hopper for receiving material for distribution having laterally extending receiving portions embracing said mast, a twin bucket hoist disposed oppositely to said hopper on said mast, mechanism for raising and lowering said hoist, said buckets discharging their contents into the receiving portions of said hopper about said mast.

5. The combination in apparatus of the character described, a rigid upright mast, means on opposed portions of said mast for receiving material for distribution, the inlets to said means positioned in the axial plane of said mast, twin buckets for elevating material arranged to be elevated and lowered on said mast, means for raising and lowering said buckets, means for simultaneously discharging said buckets, said buckets positioned for discharging their contents into said inlets whereby the impact of discharge is evenly distributed on opposed portions of said mast and in the axial plane thereof.

6. The combination in apparatus of the character described, a rigid upright mast, means on said mast for receiving material for distribution, inlets to said means arranged on opposed portions of said mast

and positioned in the axial plane of said mast, twin buckets for elevating material arranged to be elevated and lowered on said mast, means for raising and lowering said buckets, means for simultaneously discharging said buckets, said buckets positioned for discharging their contents into said inlets whereby the impact of discharge is evenly distributed on opposed portions of said mast and in the axial plane thereof.

7. The combination in apparatus of the character described, a rigid upright mast, a hopper for receiving material for distribution arranged exteriorly of the mast, said hopper having receiving branches embracing opposed surfaces of said mast, two buckets for elevating material arranged to be elevated and lowered in vertical planes passing through said branches, means for elevating and lowering said buckets and means for discharging said buckets whereby the contents of each bucket in emptying into said branches pass around said mast.

8. The combination in apparatus of the character described, of a rigid upright mast, a vertically movable carriage mounted thereon having portions extending laterally beyond the limits of said mast on two sides thereof, pivoted buckets mounted in said portions, hoisting mechanism for said carriage and buckets, a vertically adjustable hopper mounted on said mast having trip means for said buckets, said buckets positioned for discharging their contents away from said carriage and towards said mast.

9. The combination in apparatus of the character described of a rigid upright mast, a hopper having laterally extending portions for receiving material for distribution, said portions extending along the mast face at least one-fourth of the width of said face, pivotally mounted plural means for elevating material arranged to be elevated and lowered on said mast, and mechanism for elevating and lowering said means, said means positioned for concurrently discharging their contents into said portions.

10. The combination set forth in foregoing claim 2, wherein the hopper is mounted for vertical adjustment on said mast, and tripping means mounted on said hopper and movable to positions in and out of the path of said first named means.

11. In apparatus of the character described, the combination of an upright mast, a hopper for receiving material for distribution, a vertically movable frame, a hoist bucket pivotally secured thereto for elevating material arranged to be elevated and lowered on said mast, mechanism for elevating and lowering said frame and bucket, means adjacent said hopper for tilting said bucket and a single member associated with said frame and bucket for limiting the tilt.

ing movement of said bucket in two directions.

12. In a device of the character described, a rigid upright mast, an adjustable hopper thereon having laterally extending receiving portions along two sides of said mast for receiving material for distribution, said receiving portions being pivotally mounted, a plurality of buckets mounted for travel along said mast, and trip means for said buckets mounted on said pivoted receiving portions.

13. Concrete distributing apparatus comprising a mast, a hopper against one face of said mast, a hoist carriage against the opposite face of the mast, concrete receptacles on said carriage each having a discharge portion on opposite faces of said mast, said hopper having inlets on said last-named opposite faces, said inlets and discharge portions being substantially aligned substantially intermediate of said first-named faces.

14. In apparatus of the character described, the combination of an upright mast, a hopper for receiving material for distribution, a vertically movable frame, a hoist bucket pivotally secured thereto for elevating material arranged to be elevated and lowered on said mast, mechanism for elevating and lowering said frame and bucket, means adjacent said hopper for tilting said bucket and a single chain associated with said frame and bucket for limiting the tilting movement of said bucket in two directions.

Witness my hand this 28th day of October, 1927, county of Middlesex, State of New Jersey.

JAMES E. BUSHNELL.
